DESIGN FOR A DISPLAY CARD

Franz F. Ehrenhaft and Berthold Freund,
New York, N. Y.

Application December 16, 1940, Serial No. 97,344

Term of patent 3½ years

To all whom it may concern:

Be it known that we, Franz F. Ehrenhaft, a citizen of Czechoslovakia, residing at New York, in the county of New York and State of New York, and Berthold Freund, a citizen of Jugoslavia, residing at New York, in the county of New York and State of New York, have invented a new, original, and ornamental Design for a Display Card, of which the following is a specification, reference being had to the accompanying drawing, forming part thereof.

In the drawing, the figure is a front elevational view of the display card, showing our design. The heavy shading indicates contrasting colors.

The article is of no appreciable thickness and all parts thereof are substantially flush with the surface.

We claim:

The ornamental design for a display card, as shown and described.

FRANZ F. EHRENFHAFT.
BERTHOLD FREUND.
